CLAIM

The ornamental design for a hand manipulated novelty,
as shown and described.

DESCRIPTION

FIG. 1 is a perspective view of the hand manipulated
novelty embodying the design of the present invention;

FIG. 2 is a front elevational view thereof;

FIG. 3 is a rear elevational view thereof; and,

FIG. 4 is a typical side elevational view thereof, all sides
being identical to the side shown in FIG. 4.FIG. 1

FIG. 2

FIG. 3

FIG. 4
